R. F. Bourne

UNITED STATES PATENT OFFICE.

ERNEST D. ANDERSON, OF NEW YORK, N. Y., ASSIGNOR TO E. D. ANDERSON, INC., OF NEW YORK, N. Y., A CORPORATION OF NEW YORK.

LOCKING MEANS.

1,359,856.

Specification of Letters Patent. Patented Nov. 23, 1920.

Application filed June 12, 1917. Serial No. 174,192.

To all whom it may concern:

Be it known that I, ERNEST D. ANDERSON, a citizen of the United States, and resident of New York city, borough of Manhattan, 5 in the county of New York and State of New York, have invented certain new and useful Improvements in Locking Means, of which the following is a specification.

The object of my invention is to provide 10 cheap and simple means to prevent displacement relatively one to another, of juxtaposed material in a direction substantially parallel to the planes of said material.

In carrying out my invention I provide 15 two or more juxtaposed layers of material, such as sheets of paper, metal or the like, and I form a slit through such layers of material and bend such layers on one or both sides of the slit to cause edge portions of 20 said material at such slit to oppose to prevent displacement of the layers of the material in certain directions.

My invention may be embodied in different forms of devices, such as for securing 25 sheets of material of any desired size from displacement by sliding relatively to each other, or in receptacles or bags for retaining their mouths closed, and in other relations.

My invention further comprises novel 30 details of improvement that will be more fully hereinafter set forth and then pointed out in the claim.

Reference is to be had to the accompanying drawings forming part hereof, wherein, 35 Figure 1 is a perspective view illustrating two sheets of material embodying my improvements; Fig. 2 is a perspective view of a receptacle or bag constructed in accordance with my invention; Fig. 3 is an enlarged 40 cross-section substantially on the line 3, 3, in Fig. 2; Fig. 4 is a plan view of a blank from which the receptacle shown in Fig. 2 may be made, and Fig. 5 is a perspective view illustrating the manner of folding the blank for 45 the production of said receptacle.

A plurality of juxtaposed layers or sheets of material are indicated at 1, 2, shown placed one against the other, which layers are slit through at 3, and said layers are bent 50 sidewise adjacent to said slit, being shown bent in opposite directions at 4, 5, to one side of the plane of the layers, although one of such bends will suffice for some purposes.

Such slitting and bending of the layers of the material has the effect to cause the inner 55 edges of the bent portion to oppose inner edges of the opposite portion adjacent to the ends of slit 3, as well as at any intermediate positions where such edges may oppose, which prevents the displacement of 60 the layers of material laterally or edgewise relatively one to another, as in the directions of the arrows in Fig. 1.

The arrangement described may be useful 65 in different relations to prevent relative displacement of layers of juxtaposed material. I have illustrated my invention embodied in a receptacle or bag adapted to contain food products or other goods, which receptacle or bag may be made from a single sheet of 70 paper or other suitable material folded to produce the desired receptacle. The receptacle or bag is shown having a bottom 6, opposing side walls 7, 8, and intermediate end walls 9 adapted to fold between said walls. 75 Such receptacle or bag may be made by folding a blank indicated at 10, which may be made of paper. Said blank may be made waterproof, if desired, by impregnating the same with suitable wax or paraffin, or applying one or more layers of wax or paraffin thereon. In the example illustrated, the blank 10 is shown provided with spaced centrally disposed score lines 11, 12, between 80 which the bottom 6 and the end walls 9 are 85 formed, and with spaced transverse score lines 13, 14 between which and the lines 11, 12, the portions 15, 16 of the sides may be formed. Said blank is also shown having diagonal score lines 17, whereby corre- 90 sponding corner webs 18, 19 are formed, which provide outer layers of the side walls of the receptacle when the blank is folded for setting up the receptacle or bag. The latter may be set up by folding the blank on 95 said score lines in the manner illustrated in Fig. 5, so that when the parts are all folded together the receptacle or bag may appear substantially as indicated in Fig. 2. After the blank has been folded and the receptacle 100 or bag set up, the marginal layers adjacent to the mouth thereof are brought close together or juxtaposed face to face, and are bent transversely along the fold line indicated at 20 (Fig. 2), providing a laterally 105 extending mouth portion 21, comprising sev-

2

eral layers or webs of the material in lapped relation. Such projecting portion 21 is slit through the lapped layers or webs thereof, as indicated at 22, in the general direction of the outer edges 23 thereof, and between such edges and the fold or bend 20 the layers or webs of the projecting portion 21 that are between the slit 22 and the edges 23 are bent to one side of the plane of portion 21, as by being bent downwardly at 24. The layers or webs of the projecting parts 21 that are between the slit 22 and the fold 20 may also be bent to one side of the plane of portion 21, as by being bent upwardly at 25. While the bend at 24 may suffice for some purposes, it may be preferable in some receptacles to bend the layers in opposite directions, as indicated in Fig. 2. Such slitting and bending of the material of the projecting portion 21 at the mouth of the receptacle or bag has the effect to cause the inner edges of the layers of the bent portions 24 to oppose the inner edges of the layers of the opposite portion at the ends of slit 22, as well as at any intermediate positions where such edges may oppose, which prevents displacement of the layers of projecting portion 21 in a lateral or edgewise direction, as in the direction of the arrows in Fig. 2, and the abutting of the opposed wall portions or sides of the receptacle prevent displacement of said layers in an opposite direction. In the example illustrated in Fig. 3 several of the layers of projecting portion 21 of the receptacle are shorter than other layers, so that the slit 22 passes through the latter layers only. By the means described the layers of the lateral projection portion 21 of the receptacle or bag mouth are retained from spontaneous opening in the directions indicated, and the fold at 20 serves to prevent the contents from sliding out. Said fold may be squeezed or compressed or given a sort of back set to form a rather sharp edge to aid in preventing the outflow of the contents of the receptacle, and to aid in

causing the projecting portion 21 thereof to remain in a laterally disposed position.

The construction described affords an exceedingly simple and yet efficient means of preventing displacement of superposed or juxtaposed layers of material, without requiring gluing or cementing of the layers together, and when my improvements are applied in the receptacle or bag as set forth, the simple operation of folding the material at 20 and slitting and bending the layers suffices to seal the mouth of the receptacle and cause it to remain sealed. My improved receptacle when charged is adapted to be inclosed within a carton for transportation, and since the layers are held securely together moisture is excluded from the receptacle.

Having now described my invention what I claim is:—

A receptacle comprising a single piece of material folded to form a bottom, side walls and ends, and having corner portions folded and lapped along corresponding side walls, said material at the mouth portion being located close together and folded providing a lateral projection of layers of material, said layers of material having a slit therethrough extending in the direction of the outer edges of said material and distant therefrom, said folded material having layers on one side of the slit deflected from the plane of the layers on the other side of said slit presenting edges of the deflected layers in register with other layers on the opposite side of the slit, said edges extending in the general direction of the outer edges of said mouth to prevent said layers from slipping in a lateral direction upon one another.

Signed at New York city, in the county of New York and State of New York, this 11th day of June, A. D. 1917.

ERNEST D. ANDERSON.

Witness:

T. F. BOURNE.
